UNITED STATES PATENT OFFICE

CHARLES A. SHAFFER, OF CHICAGO, ILLINOIS, ASSIGNOR TO THE WATSON-STILLMAN CO., OF NEW YORK, N. Y., A CORPORATION OF NEW JERSEY

CROSSEHEAD PIN EJECTOR

Application filed October 9, 1929. Serial No. 398,540.

Important objects of the present invention are, to provide an improved jack device or press designed for lateral operation; to provide a jack device designed particularly for efficient performance of the work of removing the wrist pin from a locomotive crosshead by endwise pressure upon the pin; to provide such a jack device designed to be conveniently moved to and from the work, to be readily and accurately adjusted with relation to the work, and to be conveniently and securely attached to a fixed anchorage for resisting reaction and holding the jack in operative position; and to provide in such a device, freely adjustable and readily operable anchoring means adapted for ready connection to fixed anchorages varying in shape, size and position.

Other objects of the invention will appear hereinafter.

In the drawings, Fig. 1 is a side elevation of the jack device, showing it adjusted for operation;

Fig. 2 a plan view of the device showing it operatively connected to the connecting rod and piston rod of a locomotive;

Fig. 3 a rear view of the device;

Fig. 4 a detail section taken on the line 4—4 of Fig. 1;

Fig. 5 a section through the jack taken on the line 5—5 of Fig. 2;

Fig. 6 a section taken on the line 6—6 of Fig. 2; and

Fig. 7 a miniature side view of a locomotive with the jack device operatively connected thereto for forcing out the wrist pin.

The jack device is a unit which includes a base in the form of a wheeled truck 1. The truck structure comprises a flat metal platform 2 supported by a pair of small rear wheels 3 and a small front wheel 4. The wheels 3 are mounted upon an axle 5 rigidly secured in any suitable manner to the underside of the platform, and the wheel 4 is rotatable upon an axle 6 mounted in a fork 7.

The fork 7 is vertically swiveled in a bearing bracket 8 secured to the platform, and a forked draught tongue 9 is hinged to the axle 6. Mounted upon the platform 2 is a pedestal comprising a base plate 10, secured

to the platform, and an upstanding tubular section 11 threaded at its lower end and screwed into a threaded opening in plate 10. This pedestal forms a support for a hydraulic jack 12 and its mounting, together with anchoring devices mounted with the jack.

The jack 12 comprises a body or barrel 13 in which a ram 14 is slidably mounted. Ram 14 is formed with a reduced cylindrical end 15 which projects longitudinally from one end of the barrel 13 and is slightly concave as indicated at 16. The opposite end of the barrel forms a compression chamber 17 into which fluid is admitted for forcing the ram outward. A port 18 in one side of the compression chamber admits and exhausts the fluid. Formed in the barrel is an annular groove 19 surrounding the ram, and disposed in said groove is suitable packing 20. The jack is disposed and supported with its axis horizontal, for operation of the jack ram in a lateral direction.

A mechanism is provided for retracting the ram and includes a plate 21 rigidly mounted upon the projecting portion of the ram and formed with a radial arm extending laterally to a point beyond the outer diameter of the jack barrel. Disposed along the exterior of the barrel is a toothed rack 22 one end of which is bolted as at 23 to the plate 21. A pinion 24 is disposed beneath the rack, meshes therewith and is fixed upon a short shaft 25. Extending over said rack and pinion is a casing 26 which is secured to the jack barrel as at 27 and forms a guide for the rack and a cover for both rack and pinion. A bearing 28 for the pinion shaft 25 is formed upon said casing, and the shaft projects outwardly from the bearing and is formed with a squared end. A shaft-turning member 29 resembling a socket wrench is adapted to detachably engage with the squared end of the shaft for turning the shaft and pinion and thereby shifting the rack 21 to retract the ram after an operation of the jack.

The support or mounting for the jack includes a cross beam 30, located at the inner closed end of the jack barrel 13. The beam and barrel are preferably formed by a single

metal casting, with the barrel extending from a medial point of one edge of the beam and the beam forming two laterally extending cantilever arms 31 at oposite sides of the barrel. Said arms form supports for anchoring devices to be described hereinafter. At its under side the beam 30 is formed with a boss 32 bored out to form a vertical socket. The beam and the parts supported thereby are mounted upon a post 33 whose upper end is reduced and fitted in said socket. A pin 34 locks the beam to the socket and prevents relative turning. The lower portion of the post extends for a material length into the tubular pedestal 11, mounted upon the truck, and is fitted for vertical sliding therein but keyed against turning, as indicated at 35. The post is threaded and an adjusting nut 36 is screwed thereon and disposed to abut the upper end of the pedestal 11. Radial handles are provided upon said nut for turning it and thereby vertically adjusting the post and its supported parts.

Mounted and secured upon the truck platform 2, forwardly of the pedestal 11, is a small fluid tank 37 formed with a flat top upon which a pump 38 for operating the jack is mounted and secured. The pump structure includes a casing 39 containing the usual plunger, valve and conduit means, not shown. An operating lever 40 is connected at one end to a fulcrum link 41 pivoted to the pump casing, and at a point intermediate its ends said lever is pivoted to the plunger rod 42. The free end of the lever carries a permanent short handle 43 and a long handle 44 detachably mounted in a socket 44^a formed in the lever 40, said long handle extending laterally beyond one side of the truck. A fluid connection, not shown, leads from the tank 37 to the pump and a bendable pipe 45 leads from the pump outlet 46 to the jack barrel 13 and is connected to the port 18 thereof. At 47 is shown a handle for operating a valve within the pump which controls the return of the fluid to the tank when the jack ram is to be retracted. The pump is of standard form, or substantially so, and illustration of its interior structure is therefore omitted.

The lateral cantilever arms 31 formed by the cross beam 30 serve for the attachment and support of the anchoring devices. For this purpose each arm is formed with a horizontal slot 48 extending inwardly from its end for most of the length of the arm. These slots preferably lie within the horizontal plane of the axis of the jack. In the present case the apparatus is intended particularly for the removal of wrist pins from crossheads of locomotives. Therefore two anchoring devices 49 and 50 of different design are provided. The device 49 is designed for anchoring to the piston rod at one side of the crosshead and is provided with a single open hook 51 formed to embrace the piston rod and

make a good liberal contact with the rod to prevent injury thereof. Integrally formed with the hook is a straight, elongated shank 52 threaded as at 53 inwardly from its free end for a material portion of its length. The anchoring device 50 is designed for anchoring to the connecting rod of the locomotive, at the opposite side of the crosshead, and includes two hooks 54 disposed in reversed and opposed relation and both pivotally connected as at 55 to an eye formed upon one end of a shank 56. The remainder of shank 56 is similar to shank 52 of the other anchoring device. Hooks 54 are formed to effect a secure anchoring engagement with a connecting rod of standard form having an I-beam cross section. The pivotal connection 55 of the hooks adapts them to swing toward and from each other for opening and closing, and adapts them both to swing downward when not in use. Said pivoted connection comprises a bolt, nut and cotter pin, and by tightening the nut the hooks may be clamped in an adjusted operative position.

The shanks 52 and 56 are inserted through the beam slots 48 and each is held against endwise withdrawal by a nut 57 and washer 58 upon the threaded end thereof. The adjacent edge 59 of the beam is straight and forms a suitable abutment for said washers. Through the ends of the beam, headed pins or bolts 60 are vertically inserted to close the outer ends of the slots 48 and prevent the anchoring devices from slipping out of the slots. The design of the anchoring devices and their mounting renders them readily adjustable and universally shiftable. By turning the nuts 57 they may be adjusted longitudinally to vary their reach; they may be adjusted bodily toward and from the jack by shifting their shanks along the beam slots, and may be tilted relatively to the jack by swinging the shanks in the slots. The shanks are also rotatable in the slots for bringing the anchoring devices in proper relation to their anchorages. The two anchoring devices are interchangeably mounted to adapt the jack for connection to either side of a locomotive. Removal of said devices for interchanging them is readily effected by merely withdrawing the pins 60 and slipping the shanks of the devices laterally out of the slots 48.

In the use of the device for ejecting the wrist pin from a locomotive crosshead the truck 1, with the parts carried thereby, is rolled to operative position adjacent the crosshead. The adjusting nut 36 of the jack support is then turned, if necessary, to bring the jack ram upon a level with the wrist pin indicated at P mounted in a bore in the crosshead H. The outer end of said pin usually bears a nut and an oil cup, which are removed. Having adjusted the jack ram into alinement with the wrist pin, the single

- hook of the anchoring device 49 is engaged with the piston rod R at one side of the cross-head and the two hooks of the anchoring device 50 are engaged with the connecting rod C at a point adjacent the opposite side of the crosshead, the anchoring devices being readily shiftable and adjustable to effect a secure engagement with their anchorages and to hold the jack in proper relation to the work.
- 5 10 By working the pump lever 40 the pump 38 is operated to draw fluid from the tank 37 and force it through the pipe 45 to the compression chamber of the jack for forcing the ram outward against the end of the wrist pin P.
- 15 In the preliminary operation for merely bringing the jack ram into contact with the wrist pin the pump may be operated by means of the short handle 43. When strong resistance is encountered by the ram the pump 20 is operated by the long handle 44 to exert a powerful pressure for forcing the wrist pin inward to free it from its socket. During this powerful thrust the anchoring devices 49 and 50 resist the reaction of the jack and 25 securely hold the latter in operative position. After the wrist pin has been freed the jack device may be readily detached and removed from the locomotive.
- Heretofore the removal of wrist pins has 30 been an exceedingly difficult and tedious operation owing to the fact that the pins frequently stick so tightly in the crosshead as to require tons of pressure to free them, and owing to the fact that the means available for 35 performing the operation have been very inadequate. The present device has been designed throughout to facilitate this operation and it forms a compact, readily transportable unit for moving to and from the work. The 40 hydraulic pressure means, together with the means for directing said pressure and for resisting reaction, enables the device to apply a pressure of many tons with the utmost effectiveness and with perfect safety. At the same 45 time the design of the device avoids a heavy, bulky base structure and makes it light and compact for transportation.
- While I have shown and described a very satisfactory form of my invention, I do not 50 wish to be limited strictly to the structure described nor to the use set forth. It is obvious that the jack device is well suited for other work of a similar character. I therefore reserve the right to make such changes in structure and application as will lie within the 55 scope of the claims.
- What I claim is:
1. A hydraulic jack unit for removing the wrist pin from an engine crosshead, comprising a wheeled truck; a hydraulic jack; a mounting for said jack carried by the truck and supporting the jack elevated above the truck and disposed for operation in a lateral direction; manually operable means for adjusting the jack to different elevations; a pump mounted upon the truck for operating the jack; anchoring means connected to the jack, disposed at one side thereof and formed to anchor to the engine piston rod; and anchoring means connected to the jack disposed at the opposite side thereof and formed to anchor to the engine connecting rod, the ram of the jack being adapted to engage the wrist pin for forcing it endwise from the crosshead, and said anchoring means being adapted to resist the reaction of the jack and hold the latter against lateral displacement relatively to the crosshead. 70
  2. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and said anchoring means being adapted to resist the reaction of the jack and hold the latter against lateral displacement relatively to the crosshead. 75
  3. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and said anchoring means being adapted to resist the reaction of the jack and hold the latter against horizontal displacement relatively to the crosshead. 80
  4. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and said anchoring means being adapted to resist the reaction of the jack and hold the latter against horizontal displacement relatively to the crosshead. 85
  5. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and said anchoring means being adapted to resist the reaction of the jack and hold the latter against horizontal displacement relatively to the crosshead. 90
  6. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and said anchoring means being adapted to resist the reaction of the jack and hold the latter against horizontal displacement relatively to the crosshead. 95
  7. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and means rendering both of said anchoring means adjustable and universally shiftable to facilitate engagement with their anchorages, the ram of the jack being adapted to engage the wrist pin for forcing it endwise from the crosshead and the anchoring means being adapted to resist the reaction of the jack and hold the latter against displacement relatively to the crosshead. 100
  8. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and means rendering both of said anchoring means adjustable and universally shiftable to facilitate engagement with their anchorages, the ram of the jack being adapted to engage the wrist pin for forcing it endwise from the crosshead and the anchoring means being adapted to resist the reaction of the jack and hold the latter against displacement relatively to the crosshead. 105
  9. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and means rendering both of said anchoring means adjustable and universally shiftable to facilitate engagement with their anchorages, the ram of the jack being adapted to engage the wrist pin for forcing it endwise from the crosshead and the anchoring means being adapted to resist the reaction of the jack and hold the latter against displacement relatively to the crosshead. 110
  10. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and means rendering both of said anchoring means adjustable and universally shiftable to facilitate engagement with their anchorages, the ram of the jack being adapted to engage the wrist pin for forcing it endwise from the crosshead and the anchoring means being adapted to resist the reaction of the jack and hold the latter against displacement relatively to the crosshead. 115
  11. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and means rendering both of said anchoring means adjustable and universally shiftable to facilitate engagement with their anchorages, the ram of the jack being adapted to engage the wrist pin for forcing it endwise from the crosshead and the anchoring means being adapted to resist the reaction of the jack and hold the latter against displacement relatively to the crosshead. 120
  12. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and means rendering both of said anchoring means adjustable and universally shiftable to facilitate engagement with their anchorages, the ram of the jack being adapted to engage the wrist pin for forcing it endwise from the crosshead and the anchoring means being adapted to resist the reaction of the jack and hold the latter against displacement relatively to the crosshead. 125
  13. A jack device for removing the wrist pin from an engine crosshead, comprising a base; a jack; a mounting for said jack carried by the base and supporting the jack elevated and disposed for operation in a lateral direction; means for adjusting the jack to different elevations; means for operating the jack; anchoring means connected to the jack, disposed at one side thereof and formed to anchor to the engine piston rod; and anchoring means connected to the jack, disposed at the opposite side thereof and formed to anchor to the engine connecting rod, the ram of the jack being adapted to engage the wrist pin for forcing it endwise from the crosshead, and means rendering both of said anchoring means adjustable and universally shiftable to facilitate engagement with their anchorages, the ram of the jack being adapted to engage the wrist pin for forcing it endwise from the crosshead and the anchoring means being adapted to resist the reaction of the jack and hold the latter against displacement relatively to the crosshead. 130

shiftable for engagement with their anchorages, said devices being adapted to resist the reaction of the jack and hold it against displacement relatively to the crosshead.

5. A jack device for removing the wrist pin from an engine crosshead, comprising a jack provided with a ram adapted to engage the wrist pin for forcing the latter endwise; anchoring devices connected to said jack for anchoring to adjacent relatively fixed parts of the engine and adapted to resist the reaction of the jack and hold it against displacement relatively to the crosshead; and means rendering said anchoring devices shiftable and adjustable for proper engagement with their anchorages.

6. A jack device comprising a jack; anchoring devices connected to said jack and adapted to engage fixed anchorages and to resist the reaction of the jack and hold it in place during the operation thereof; and means rendering said devices adjustable and universally shiftable for engagement with their anchorages.

7. A jack device comprising a jack provided with a ram; means supporting said jack for operation of its ram in a lateral direction; a pair of anchoring devices connected to the jack and adapted to be connected to a fixed anchorage for resisting reaction and holding the jack against displacement when it is operated; means supporting said anchoring devices at opposite sides of the jack for bodily shifting toward and from the jack laterally thereof, and for lateral swinging with relation to the jack; and adjusting means for varying the reach of the anchoring means.

8. A jack device comprising a jack provided with a ram; a pair of arms in fixed relation to the body of the jack, extending laterally from opposite sides thereof and each formed with a slot therealong; a pair of anchoring devices, each formed with a shank disposed in one of said slots for bodily shifting of said devices laterally toward and from the jack and for swinging laterally of the latter; and nuts threaded upon said shanks to form pull connections with said arms and for varying the reach of the anchoring devices, the anchoring devices being formed to engage fixed anchorages to resist reaction and hold the jack against displacement when it is operated.

9. A hydraulic jack unit for removing the wrist pin from an engine crosshead, comprising a wheeled truck; a hydraulic jack; a mounting for said jack carried by the truck and supporting the jack elevated above the truck and disposed horizontally for operation in a lateral direction; manually operable means for adjusting the jack to different elevations; a pump mounted upon the truck for operating the jack; adjustable and removable hook-shaped anchoring means connected to the jack, disposed at one side thereof

and formed to engage the engine piston rod; and adjustable and removable hook-shaped anchoring means connected to the jack disposed at the opposite side thereof and formed to anchor to the engine connecting rod, the ram of the jack being adapted to engage the wrist pin for forcing it horizontally endwise from the crosshead, and said anchoring means being adapted to resist the reaction of the jack and hold the latter against horizontal displacement relatively to the crosshead.

10. A jack device for removing the wrist pin from an engine crosshead, comprising a base; a jack; a mounting for said jack carried by the base and supporting the jack elevated and disposed for operation in a lateral direction; means for operating the jack; and a pair of anchoring devices connected to the jack and interchangeably mounted at opposite sides thereof, one of said devices being formed to anchor to the engine piston rod and the other being formed to anchor to the engine connecting rod, the ram of the jack being adapted to engage the wrist pin for forcing it endwise from the crosshead, and said two anchoring devices being adapted to resist the reaction of the jack and hold the latter against displacement relatively to the crosshead.

In testimony whereof I hereunto affix my signature.
